UNITED STATES PATENT OFFICE.

ERNEST L. BROOME, OF TARRYTOWN, NEW YORK, ASSIGNOR TO GENERAL REDUCTION GAS & BY-PRODUCTS COMPANY, OF NEW YORK, N. Y., A CORPORATION OF DELAWARE.

GAS-PRODUCING APPARATUS.

Application filed January 17, 1921. Serial No. 437,667.

Fig. 1 is a central, longitudinal section of a gas generator embodying my invention; Fig. 2 is a section on lines II—II of Fig. 1, but with the extractor rotated through 270° 5 from the position shown in Fig. 1; Fig. 3 is a section similar to Fig. 2, but with the cylinder rotated through approximately 240° from the position of Fig. 2; Fig. 4 shows a rear elevation of the ash and clinker 10 extractor; Fig. 5 is a side elevation thereof partly in section; and Fig. 6 is a front elevation, partly in section, showing the manner of discharging clinkers, ash, or coke from the extractor.

15 My invention relates to gas generators, and particularly to a machine designed for use with low-grade or otherwise waste fuel, such as washery silt, bone coal, slack, coke breeze, sawdust, tanbark, peat, or lignite. 20 My improved machine may be employed either to generate producer or water gas or a mixture of both, or to oxidize or reduce material, or to devolatilize fuel for making briquettes.

25 My invention contemplates using my machine in such manner that the machine is only partially filled with fuel, sufficient space between the fuel and the inside surface of the upper part of the lining of the cylinder 30 being maintained, to permit the fuel to turn over freely as the cylinder revolves, thus causing a constant shifting of the fuel body and the bringing of new fuel constantly into the area of activation.

35 My invention further consists in a novel means and method of removing ash, coke and clinkers from the cylinder, and in the various features which I shall hereinafter describe and claim.

40 Referring to the drawings, I have shown my improved generator with its axis arranged at such an angle of inclination that in all cases it is only partially filled. In the generator 2 is a metal shell or casing, adapted to be rotated by any well-known means, which has a refractory lining 3. At the end of the casing through which the fuel is admitted the cylinder has a relatively large opening 4, and in this opening is arranged 45 a screw conveyer 5, by which the material is admitted into the vessel. This screw conveyer is mounted in a stationary hood 6 of greater diameter than the end of the casing. The hood has an open side 7 into which

the feed end of the cylinder extends for some 55 distance, so as to permit the location of the flexible joint 8 as far as possible away from the open end of the vessel, thereby keeping it as cool as possible and minimizing the deposition of fine fuel and dust in the joint. 60 The opening 4 is made as small as the volume of the offgoing gas will permit, with the object of forming a dam and preventing the back-spill of fuel into the hood 6, and at the same time allowing as high a surface 65 and consequent depth of fuel as practicable. The hood on its under side has a pocket 9, preferably equipped with a slide or valve 10. This pocket is employed for the purpose of ascertaining whether the feed of the fuel is 70 too fast, since if too much fuel is fed into the cylinder it will back-spill out of the opening 4 and will drop down into the pocket 9.

The vessel at its discharge end has a central aperture 11 through which a stationary tuyère 12 projects into the interior of the vessel. I prefer to make the tuyère 12 out of two pipes of different diameters, welded together at their inner ends, so that a water 80 cooling channel 13 may be provided in the space between the pipes. The inner end 14 of the tuyère is preferably bent downwardly so as to direct air or other activating agent downwardly into the depths of the fuel 85 bed and at the same time act as a means to stir and agitate the fuel as the cylinder revolves. I have found it desirable that the tuyère 12 shall extend away from the lining, so as to prevent such clinker as is formed 90 from adhering to the lining, and also to prevent the activating agent from escaping uncombined along the surface of the lining.

To save weight and head room, I prefer to construct my cylinder with a relatively 95 small diameter near the feed end, as such end normally serves the purpose of acting as a conveyer, dryer, and progressive heater, which I have designated as the portion A. I have found it desirable to so construct the 100 cylinder that at the point which contains the zone of greatest temperature the cylinder will be approximately two to two and a half times the diameter at the feed end, and I have designated this portion of the cylinder 105 as B.

I have found it desirable, in order to lengthen the path of the offgoing gases

through the fuel (which not only serves to give better heating efficiencies and fixes the volatile gases, but also results in a greater reduction to CO when producer gas is being manufactured), to employ a baffle 15 in the section between the zone of most intense heat B and the drying and preliminary heating zone A. The baffle 15 has an opening 16 of sufficiently less diameter than the diameter 10 of the cylinder so that the top of this opening 16 is always normally below the top surface of the fuel, so as to require the offgoing gases to pass under the surface of the fuel on their way out of the cylinder.

15 Arranged about the periphery of the cylinder are the ash and clinker extractors 17, of which for the purpose of illustration I have shown but one, although as many as desired may be employed. The extractor consists in 20 three elements: one element 18 of which opens directly into the cylinder on a radius thereof; the second element 19 is arranged substantially parallel with the axis of the cylinder, and at right angles to the first element; and a third element 20 attached to 25 the second element and substantially at right angles to both the first and second elements. The open end of the element 20 is closed by a hinged cover 21 arranged to be opened by 30 the action of the latch 22 engaging the stationary trip or stop 23. The cover is closed and held shut by the spring 24 after the latch 22 is disengaged from the trip 23. The end wall of the cylinder is provided with 35 detachable doors 25 through which access to the interior of the machine may be obtained.

In the operation of my improved machine, in beginning operations a fire may be kindled 40 in the portion B by fuel inserted through a door 25. Then, when the compartment B has been sufficiently heated to cause combustion, fuel is fed in through the conveyor 5 and is advanced by the rotation of the vessel toward its lower and larger end, building 45 up in the portion A a fuel bed to a considerable depth against the baffle 15 and working through the baffle into the lower end B, where, by reason of the formation of the cylinder, the fuel bed is still deeper. It is 50 desirable to keep the fuel bed at such a depth that the gas in passing through the opening 16 in the baffle 15 will be compelled to pass below the surface of the fuel and thereby assist in the gasification process. As the fuel 55 advances through the chamber A any moisture it contains will be dried out and carried off, and a considerable proportion of the amount of heat generated in the chamber B will be absorbed in the fuel in the chamber A, as the offgoing gases pass through it, so that the material will become progressively hotter as it approaches the chamber B and as it enters the chamber B it will be 60 at a high temperature and when brought into intimate contact with an activating agent 65

such as air, steam or gas, which is delivered through the tuyère 12 into the chamber B in sufficient quantities to produce combustion, the carbon in the fuel will combine chemically with the elements in the activating agent to form H₂, CO, or CO₂, either separately or in various proportions, or to heat the contents of the vessel. As it is desirable to expose the fuel to the activating agent as completely as possible, this is accomplished 70 by the deep fuel bed through which the activating agent must pass and by causing the gas to travel underneath the surface of the fuel by means of the baffle 15.

During the gasification of the fuel as the 80 carbon becomes exhausted the remaining ash approaches a plastic state, and its particles have a tendency to adhere together, with the result that these particles do adhere together and, as the charge is rolled over and over by the rotating movement of the retort, they assume the form of balls 85 26. These clinker balls 26 accumulate around the periphery of the cylinder and, in consequence, are constantly being exposed upon 90 the surface of the fuel as the cylinder rotates. As these clinker balls become exposed at the top of the slope which the surface of the material assumes because of the rotation of the vessel as is shown in Fig. 95 2, these balls roll rapidly down to the toe of the slope, where they are constantly accumulating, so that there is always an accumulation of loose clinker balls of varying 100 sizes at the toe of the slope, which, because of the longitudinal inclination of the vessel, is the lowest point of the surface of the material. The ash and clinker extractor 17 is located at this low point, so that with each 105 revolution down to this low point, a portion of the clinkers will roll down the slope of the material into the first element 18 of the extractor, as is shown in Fig. 2. The second element 19 of the extractor has a sufficient inclination so that the balls will feed 110 slowly down this incline when they have entered from the first element, and will pass out into and through the third element 20 when the gate or cover 21 is opened by the trip 23. When the extractor rises above 115 the surface of the fuel, as it revolves upwardly with the cylinder the clinker and other material in the first element 18 will roll out of the extractor and down the slope as is shown in Fig. 3, but the material 120 which has already worked into the second and third elements will remain there until pushed outward by succeeding material rolling into the first element. As is shown in Fig. 6, the angle of repose of the material in the third element controls or limits the 125 amount of material discharged.

The clinker extractor has also a selective action, since as the vessel rotates the clinker balls because of their greater size 130

and weight will roll down the slope of the material more rapidly than the smaller particles of the material and will roll into the first element 18 of the extractor before 5 such smaller particles. Then as the rotation continues the smaller particles will follow the clinker balls into the element 18. Not all of the material which thus fills the element 18 works into the second element 19 10 on each rotation, but that part of it, comprised mainly of finer particles, which is nearest the entrance into the element 18, falls back into the interior of the vessel as the element is again rotated around the 15 upper half of the circumference of the vessel.

The various gaseous products evolved by the treatment just described are led off through the gas outlet 26.

20 I have found that my improved process and apparatus are of particular advantage with finely divided fuels, which, by the free and constant movement of the fuel bed, will have sufficient porosity for devolatilization 25 or gasification.

The gradual heat increment to which the fuel is subjected permits the recovery of the lighter volatiles such as ammonia, as well as the heavier oils and tars, each of which will 30 escape with the offgoing gas at its proper temperature and may be recovered outside the generator by fractional condensation or distillation.

35 My improved apparatus may be employed for the generation of gas from carbonaceous materials, for the volatilization and recovery of by-products from solid material containing volatile products, or for the production of coke from which briquettes can 40 be manufactured.

I have found that very efficient results 45 can be obtained by preventing the fuel from accumulating at too high a level in the cylinder. By keeping the top surface of the fuel at a distance below the lining in the upper part of the cylinder in the activation zone which is accomplished by having the long axis of the generator at a not too great deviation from the horizontal, the fuel is 50 permitted to stir itself freely by constantly being turned over, a condition, which would not obtain if the cylinder was filled full to its upper side.

The terms and expressions which I have 55 employed are used as terms of description and not of limitation, and I have no intention, in the use of such terms and expressions, of excluding any equivalents of the features shown and described, or portions thereof, but recognize that various modifications are possible within the scope of 60 the invention claimed.

What I claim is:

65 1. Gas producing apparatus comprising a vessel mounted for rotation on a substan-

tially horizontal axis having an intake for the material to be gasified, a gas outlet, a clinker discharging means opening through the periphery of the vessel and extending outwardly therefrom, rotatable therewith 70 and operable by the rotation of the vessel, whereby clinkers are discharged from the free surface of the material through said clinker discharge to the exterior of the vessel, and a tuyère projecting through an end 75 of the vessel.

2. Gas producing apparatus comprising a rotary vessel having an intake for the material to be gasified, a gas outlet, and gravity operated clinker discharge means opening 80 through the periphery of the vessel forming a passage from the interior of the vessel to the exterior thereof, whereby clinker from the free surface of the material is discharged from within the vessel by the action of 85 gravity, the intake of said means being rendered inoperative by the action of gravity during a portion of each revolution of the vessel during which the said means is above the horizontal axis of the vessel. 90

3. Gas producing apparatus comprising a rotary vessel having an intake for the material to be gasified, a gas outlet, and a clinker offtake, said offtake being located on the periphery of the vessel and rotatable 95 therewith, said offtake formed of elements, one extending through the shell of the vessel and exteriorly thereof, the element extending through the shell arranged to be filled and emptied with each rotation of the vessel, and other elements of the offtake connected with the first named element outside the vessel whereby the material is discharged exteriorly of the vessel. 100

4. Gas producing apparatus comprising a 105 rotary vessel having an intake for the material to be gasified, a gas outlet, a discharge outlet at the opposite end arranged on the periphery of the vessel and rotatable therewith, said discharge outlet having one portion arranged on a radius of the vessel, and having an extended portion outside the exterior of the vessel arranged at an angle to said radial portion to permit the waste material to remain in a portion of said discharge outlet regardless of the position of the cylinder and the outlet. 110

5. Gas producing apparatus comprising a rotary vessel having an intake and an offtake for the material, a gas outlet, the offtake being rotatable with and located on the circumference of the vessel and extending from the inside of the vessel to the exterior thereof, said offtake being comprised of three elements the axis of each of which lies 115 in a plane at an angle divergent to the other two. 120

6. Gas producing apparatus comprising a rotary vessel having an intake and an offtake for the material, a gas outlet, the off- 130

- take being located on the periphery of the vessel and rotatable therewith and having a receiving portion extending from the interior to the exterior of the vessel, a further portion of the offtake connected to the receiving portion, the receiving portion being arranged to receive clinker balls from the free surface of the material in the vessel and pass such balls into the farther portion of the offtake for discharge without the vessel, the receiving element being also arranged to return within the vessel the material remaining in it on further rotation of the vessel.
7. Gas producing apparatus comprising a vessel mounted for rotation on a horizontally extending axis having an intake for the material to be gasified, a gas outlet, the opposite end being in the form of a gas-tight end wall forming a component part of the body of the vessel, the said end wall being uninterrupted except for a tuyère for an activating agent, a preheating zone near

the intake and an activating zone near the said end wall, and an outlet for waste material at a point in the circumferential wall in the activating zone of the vessel and extending outwardly therefrom, the said outlet being capable of receiving waste material during a portion only of each rotation of the vessel.

8. Gas producing apparatus comprising a vessel mounted for rotation about a substantially horizontal axis having an intake for the material to be gasified, a gas outlet, and an offtake for the waste material secured to and projecting outwardly through the shell of the vessel and rotatable therewith, the said offtake comprising a number of connected portions arranged end to end and forming a tortuous channel, one of said portions being arranged so as to retain the material therein regardless of the angle of elevation of the offtake.

ERNEST L. BROOME.
